UNITED STATES PATENT OFFICE.

DANIEL F. CARMICHAEL, OF MINNEAPOLIS, MINNESOTA.

COMBINATION-LOCK.

1,292,249.

Specification of Letters Patent. Patented Jan. 21, 1919.

Application filed July 5, 1917. Serial No. 178,814.

To all whom it may concern:

Be it known that I, DANIEL F. CARMICHAEL, a citizen of the United States, residing at Minneapolis, in the county of 5 Hennepin and State of Minnesota, have invented certain new and useful Improvements in Combination-Locks; and I do hereby declare the following to be a full, clear, and exact description of the invention, such 10 as will enable others skilled in the art to which it appertains to make and use the same.

My invention relates, broadly, to permutation or combination locks, but more particularly, to that type wherein various movements necessary to work the proper combination are effected by manipulation of a single knob or manually operated actuator. The present lock is a radical departure from 20 the well known rotary tumbler lock, in that the knob or actuator is not mounted for simple rotary motion, but is capable of movement in any one of several different directions. Generally stated, however, the 25 lock is capable of universal use wherever relatively movable parts will be locked together and released, or circuit connections are to be controlled.

The accompanying drawings illustrate the 30 lock mechanism proper in what is believed to be its preferred form and several different applications of this lock mechanism are also illustrated.

Referring to the drawings, wherein like 35 characters indicate like parts throughout the several views,

Figure 1 is a perspective view showing the lock inclosed within its casing;

Fig. 2 is a longitudinal vertical section 40 taken centrally through the lock;

Fig. 3 is a transverse section taken on the line 3—3 of Fig. 2;

Fig. 3^a is a fragmentary view in side elevation showing the lock for securing the 45 removable shell of the case to its base;

Fig. 4 is a horizontal section taken approximately on the line 4—4 of Fig. 3, some parts being removed and some parts being indicated by dotted lines only;

50 Fig. 5 is a view showing the case section on the line 5—5 of Fig. 2, but showing certain other parts in plan view, some other of the parts being removed;

Fig. 6 is a fragmentary view partly in elevation and partly in vertical section on 55 the same line as Fig. 2, certain parts being shown on an enlarged scale;

Fig. 7 is a horizontal section on the line 7—7 of Fig. 6, showing the guide for the 60 rocking so-called actuating arm;

Figs. 8, 9 and 10 are diagrammatic plan views with some parts sectioned on the irregular line 8—10 of Fig. 6, said views illustrating different relative positions of tumbler, ratchet wheel and actuating arm; 65

Fig. 11 is a horizontal section on the line 11—11 of Figs. 2 and 12;

Fig. 12 is a transverse section on the line 12—12 of Fig. 11, showing certain parts of the lock by which the center case is fastened 70 to its base, as indicated in Fig. 3^a, also showing the actuating arm in action, certain other parts being removed;

Fig. 13 is a horizontal section taken through the lock approximately on the irregular horizontal line 13—13, of Fig. 12, 75 looking upward from the base;

Fig. 14 is a detail in plan with some parts broken away, showing gears found in the vicinity of the line marked 14—14 on Fig. 6; 80

Fig. 15 is a section on the line 15—15 of Fig. 14;

Fig. 16 is a view partly in plan but with some parts in horizontal section showing the lock in some respects modified, and thereby 85 adapted for use, for example, as a door lock;

Fig. 17 is a fragmentary vertical section on the line 17—17 of Fig. 16;

Fig. 18 is a horizontal section on the line 90 18—18 of Fig. 17;

Fig. 19 is a front edge elevation of the lock shown in Fig. 16 illustrating the manner of its application to a door;

Fig. 20 is a view corresponding to Fig. 17 95 illustrating a slight modification;

Fig. 21 is a view corresponding to Fig. 16, but illustrating a modification of certain features of the lock whereby it is especially adapted for use, for example, as a transmission lock for automobiles; 100

Fig. 22 is a side elevation of the lock shown in Fig. 21, some parts being in vertical section on the line 22—22 of Fig. 21;

Fig. 23 is a detail in horizontal section on 105 the line 23—23 of Fig. 22, also indicating

the relation of parts 54 and 55 thereto, and the operation of the burglar alarm in the modification;

Fig. 24 is a section on the line 24-24 of Fig. 23; and

Fig. 25 is a diagrammatic vertical section illustrating the lock, Figs. 21 to 24, as applied to an automobile.

Referring first to the construction and ar-

- 10 arrangement illustrated in Figs. 1 to 15, inclusive, the numeral 26 indicates the base and the numeral 27 the removable shell of the lock casing. Rigidly secured to the base 26 within the shell 27 is a skeleton framework 15 28 which comprises as its chief element, a skeletonized top plate 28^a, but also comprises other bearings and features which will be hereinafter noted. As shown, the shell 27 is arranged to be locked directly to latch plate 20 30 adjustably attached to the plate 28^a as shown in Figs. 11 and 13, and hence, is directly locked to the base 26, by a latch device best shown in Fig. 3 but also indicated in Figs. 11, 12 and 13, which latch device 25 comprises a depending beveled nose hook lug 29 on the inside of the said shell 27 and a coöperating spring-held latch plate 30 slidably mounted on the said plate 28^a, which latch plate 30 is operated by movement of 30 the piston 76 against the lever 74 when lever 74 has been brought into proper relative position by operation of the stud 73 on disk 54.

Rigidly secured to and projecting from the base 26 is a stud 31 on which is a sleeve that 35 connects for common rotation an upper beveled gear 32 and lower spur gear 33, and upon which sleeve is loosely journaled a beveled gear 34.

- The numeral 35 indicates an annular bearing plate secured by suitable legs to the base 26 and surrounds the loose beveled gear 34 with ample clearance. A small bearing arm or bracket 36 is rigidly secured to the plate 35 and projects radially inward between the 40 two bevel gears 32 and 34. The said gear 32 is made hollow and is thus formed with a cylindrical inner surface that is engaged frictionally by a frictional retaining dog 37 (see particularly Figs. 6 and 14), that is pivoted 45 to the inner end of the said arm 36 and is provided with a long curved tail 37^a. A coiled spring 38 suitably anchored to the base, and, as shown, connected to the free end of the tail 37^a by a link 38^a, normally 50 holds the retaining dog 37 in frictional engagement with the coöperating surface of the beveled gear 32. Hence, normally, the said retaining dog 37 will yield and permit movements of the gear 32 in the direction of 55 the arrow marked on Figs. 4 and 14, but will prevent reverse rotation thereof, by a frictional clutch action. The loose gear 34 has an upwardly projecting stud 39 (see particularly Figs. 6 and 14) that is engageable with the 60 free end of the tail 37^a to release the retain-

ing dog 37 at the time and under conditions hereinafter noted. For temporarily holding the retaining dog 37 in a released position, under conditions hereinafter noted; a light spring latch arm 40 (see Figs. 14 and 15) is 70 anchored at one end to bearing arm 36, and at its free end has a shoulder 40^a that is engageable with a shoulder 37^b of said retaining dog.

The gear 32 has a depending cam lug or 75 stud 32^a that is engageable with an upwardly bulged cam-acting portion of the latch 40, to release the same from said dog, as hereinafter described.

In mesh with the upper gear 32 and circumferentially spaced around the same is a plurality of tumbler actuated gears 41; and likewise, grouped around and in mesh with the loose gear 34 are ratchet actuated gears 42. The corresponding tumbler actuated 80 and ratchet actuated gears are grouped together and are mounted on common shafts 43, and, inasmuch as the gears 32 and 34 are beveled gears, the said gears 41 and 42 are also beveled gears. The gears 42 are rigidly 85 secured to lower end portions of oblique shafts 43, and the gears 41 are loosely journaled on the same shafts. The oblique shafts 43 stand in planes that radiate from the axis of the fixed stud 31, and at their 90 lower ends, they are journaled in bearings 35^a on the annular bearing plate 35, while at their upper ends, they are journaled in bearings 44^a of a bracket 44 which is rigidly secured to one of the end walls or plates of 100 the frame 28.

Small ratchet wheels or segments 45 are rigidly secured to the upper end portions of the oblique shafts 43. The gears 41 are provided with sleeve-like hubs, upon which 105 cam-like so-called tumblers 46 are rigidly, but adjustably secured by set screws, or otherwise. Spacing washers or rings 47 (see Figs. 2, 3 and 6) are adapted to be placed between the tumblers and gears 41, as shown 110 at the right in Fig. 6, for example, or between the said tumblers 46 and ratchet wheels 45, as shown at the left in Figs. 2 and 6, for example. Obviously, the placing of the washer 47 determines the altitude of 115 the tumbler 46 on the hub of the gear 41. This, as will hereinafter be noted, constitutes means for changing the order of the combination.

The lower gear, to wit, the spur gear 33, 120 through an intermediate spur pinion 48, is connected to a spur gear 49 secured on the lower end portion of an upright shaft 50, journaled in its lower end in the base 26 and at its upper end in the bearing plate 28^a. 125

An upwardly spring pressed flange clutch head 51 is secured to rotate with the shaft 50 but permitted a limited vertical movement thereon by a slot and pin coupling 52 (see Fig. 2). The flange of this clutch head 51 is

has one or more pins 53 (see Fig. 4) that are adapted to be inserted through any one of a multiplicity of circumferentially spaced perforations 53^a (see Fig. 4) formed in a disk-like member 54 that is rotatably adjustable on the shaft 50, but is thus caused to rotate with the said shaft. This disk 54 carries a cam projection or cam-acting element 55 (see Figs. 4, 11 and 13) which, as shown, 10 is in the form of a roller-equipped stud. This stud 55 is operated on the reversely beveled cam surface 56^a of a sliding bolt 56 (see Fig. 13). This sliding bolt 56, in some forms of the lock might be the lock bolt itself, but in the present instance, it is utilized 15 as a carrier for an electric contact that constitutes a part of an electric circuit which is to be controlled, and which may be assumed, for illustration, to be the ignition circuit of an explosive engine used in an automobile. This sliding bolt 56, as shown, is connected 20 to the bearing plate 28^a by screw and slot connections 56^b (see Figs. 2 and 11). Said sliding bolt 56 is yieldingly retracted or 25 pulled toward the left by a coiled spring 57 (see Fig. 13).

It will now be understood that the sliding bolt 56 will be moved into a position to perform a desired function, such as to close an 30 electric circuit (see Figs. 11 and 13) or withdraw a bolt of a door lock (see Figs. 16, 17 and 18), or with the latch thrust bolt (see Figs. 21, 22 and 23), when the shaft 50 and disk 54 are given the proper predetermined 35 number of steps of rotation required to throw the stud 55 into direct contact with the central portion of the cam surface 56^a. Obviously, the number of steps of movement required to effect this result may be varied 40 by adjusting the said disk 54 in its relation to the coupling head 51.

It will be noted, that there are in this device, as illustrated, two independent sets of gears, to wit, the gears 41, 32, 33, 48 and 49, 45 which may be treated as the combination gears, and the ratchet wheels or segments 45 and gears 42 and 34 which may be treated as the releasing or restoring gears. Springs or other yielding devices will be provided for 50 normally holding and for restoring to normal positions both sets of gears. For thus restoring or returning to normal or to zero position, the tumblers 46 and combination gears, for illustration, a coiled spring 58 of 55 the clock-spring type, is anchored at its outer end to a bracket 59 on the frame 28, and at its inner end is attached to the head of the coupling head 51, or to any other part that rotates with the shaft 50. The means 60 for returning the gears 42 and 34 to normal or zero position is illustrated only in Fig. 10, and as there illustrated, comprises a coiled spring 60 suitably anchored at one end, to bracket 44, or otherwise, and at its other 65 end, attached to an arm 45^a of one of the

ratchet segments 45 and yieldingly holds said arm against a fixed stop 61 projecting from bearing plate 44, or otherwise. Obviously, since all of the ratchet wheels or segments 45 are in fixed relation to shafts 43 70 and the gears 42 and 34 which are geared or connected for simultaneous rotation, a device that restores one thereof to normal position will also restore the others to normal position. Here it may be stated that the 75 ratchet wheels 45 are not given complete rotations but are oscillated only to approximately ninety degrees, and hence, may all be segmental.

It has already been made clear that the 80 several groups of axially aligned gears, ratchet wheels and tumblers are located radially outward of and are circumferentially spaced around the projected axis of the fixed stud 31. For coöperation with these 85 circumferentially spaced ratchet wheels and tumblers, I provide so-called actuating fingers carried by the oscillating free or lower end of the stem of a so-called rocking actuator arm. This actuator arm comprises a 90 stem 62 which, at its upper or outer end, has a knob 63 and below said knob, has a fulcrum sleeve 62^a to which it is connected by longitudinal slot and pin connections 64^b that permits said stem to move axially to the 95 desired extent through said sleeve 62^a but holds the same against rotation in respect thereto. This sleeve 62^a, by means of diametrically extended trunnions 64^a, is pivoted to a fulcrum ring 64, which, in turn, by diametrically opposite trunnions 64^b that are ninety degrees to said trunnions 64^a, is pivoted to lugs 65 on the bearing plate 28^a. In this way, the actuator arm or stem 62 is mounted on a universal joint, but, nevertheless, it is regulated in its movements and is restored from its oscillatory movements to a 100 central normal position by means of a guide plate 66 which has guide slots 66^a (see Figs. 6 and 7) that radiate in four directions, to 110 wit, each from the projected axis of the stud 31 toward the projected axis of one of the oblique shafts 43.

To the lower or free end of the stem 62 is attached a sleeve-like head 67 that is provided with four radially projecting ratchet engaging fingers 68 and four similar gear tumbler actuating fingers 69, for a purpose presently to be noted. The head 67 is mounted on the stem 62 with freedom for 115 slight oscillatory movement permitted by a slot and pin connection 67^a (see Fig. 6). A coiled spring 67^b secured to the stem 62 and head 67 yieldingly holds the same in normal position. On the stem 62 is a guide 120 collar 62^b which, by axial movements of the stem 62, is adapted to be set either just above or just below the curved guide plates 66. In Figs. 2 and 3, the numeral 70 indicates a curved guard plate loosely 130

surrounding the stem 62 and serves to keep closed the enlarged opening in the shell 27 through which the said stem works with sufficient clearance to permit its required oscillatory movements. The lock will sometimes be used with the actuating arm or stem 62 set in an upright position, or at an angle, and it will sometimes be applied with the said stem normally set in a horizontal direction, as, for example, when the lock is applied to a door. In any of these arrangements, it is desirable that yielding means be provided for normally holding the said actuating arm in its neutral position or aligned with the stud 31. This may be accomplished in different ways, as for example, by means of a multiplicity of spring fingers 71 secured to the guide plates 66 in rectangular arrangement, each crossing one of the guide channels 66^a.

The operation of the lock so far described, is substantially as follows:

From what has been stated, it will be understood that the actuating fingers 68 and 69 may be given oscillatory movement in any one of four directions and may be raised and lowered from one position into another, making in all, eight successive combinations of movements in the working of the lock mechanism, as here illustrated. The combination is set, as desired, by giving the desired rotary and axial adjustments to the tumblers 46 and to disk 54. In the proper working of the combination, it is necessary to bring the proper actuating fingers 69 into action on coöperating tumblers 46 in the proper order, to wit, in an order that will cause the operative finger 69 to engage the cam surface and adjust the lug of the coöperating tumbler 46. For instance, if the operation in working the lock, is properly performed, the finger 69, that it thrust laterally by an oscillatory movement of the stem 62 toward the selected tumbler 46, will engage the cam surface and lug of such coöperating tumbler 46 in the position shown in Fig. 8 by full lines, and will move the said tumbler 46 to the position shown in Fig. 9. Under this movement, the cam surface of the said tumbler 46 will carry the corresponding finger 68 clear of the teeth of the coöperating ratchet 45, and when the actuator arm is returned to normal or neutral position, the said cam surface will still prevent the said finger 68 from engaging the said coöperating ratchet 45. The working of the combination requires such movements of the actuator arm as will progressively engage fingers 69 with tumblers 46 which are in operative position, as shown in Fig. 8. To effect this engagement it will sometimes be necessary to oscillate the actuator arm or stem 62 in some one direction with the fingers 68 and 69 lowered, as shown by full lines in Fig. 6, and if will

sometimes be necessary to perform such oscillations with the said fingers 68 and 69 in the raised position indicated by dotted lines in Fig. 6. This statement assumes that some of the tumblers 46 are set in low and some in high positions. The above noted movement of the fingers 68 and 69 from position shown in Fig. 8 to position shown in Fig. 9, produces a slight oscillation of the head 67 on the actuator arm or stem 62 against the tension of the spring 67^a. Then by the proper operating manipulations, the stud 55 of the disk 54, operating on the cam surface 56^a, will move sliding bolt 56 to its extreme position to the right, as illustrated in Fig. 13. For example, this operation may be one in which the said sliding bolt 56 will either lock or unlock a door, for example, or it may be an operation in which the sliding bolt 56 will either close or open an electric circuit. This complete operation of the sliding bolt 56 can be made only by a person knowing the combination for which the lock is set.

If, in attempting to operate the combination, there is a mistake made in the proper order or manner of manipulation, then when a certain pair of fingers 68, 69 are thrust laterally, there will be no tumbler 46 standing in position to be engaged by the finger 69, and hence, the finger 68 will be engaged with one of the teeth of a coöperating ratchet 45 and the said ratchet 45 will be given a step of movement against the tension of the spring 60. This movement of the ratchet 45, or any one thereof, will be transmitted to the gears 41 and 34 and such movement imparted to said gear 34 will throw its stud 39 against the free end of the tail 37^a of the retaining dog 37, (see Fig. 14), and thereby positively release the said retaining dog from gear 32. The spring 40 then temporarily latches the retaining dog 37 in its released position which permits spring 58 (see Figs. 2 and 4) operating through shaft 50 and gears 49, 48, 33, 32 and 41, to instantly restore all of the tumblers 46 to their normal or zero positions.

Just before the gear 32 reaches the extreme of its backward movement to zero, its lug 32^a (see Fig. 15), striking the bulged portion of spring 40, will release the same from retaining dog 37, and thereupon, spring 38 will again render the said retaining dog operative on gear 32, so that it will hold the same in the different positions in which it will be set, step by step, under proper operation of the combination. A stop shoulder 72 on the disk 54 engages a fixed stop 72^a to limit the backward rotation of the combination gears to zero position (see Fig. 4).

To restore the combination or locking parts to zero or normal lock position after the combination has been properly operated to open or unlock the lock, it is only neces-

sary to produce any one of the several operations required to engage one of the fingers 68 with a coöperating ratchet 45.

Preferably, a finger and tumbler movement performed after the combination has been properly operated to unlock the lock, will be utilized to release the casing lock (see Fig. 3^e). Such manipulation would cause one further step of rotary movement 10 of the disk 54, thereby causing a pin 73 on said disk to engage one end of a thrust lever 74 that is pivoted to a latch plate 30 mounted to slide on the bearing plate 28^a, as already noted, and subject to springs 75. 15 76 indicates a spring-pressed plunger or piston mounted in a suitable fixed bearing in position for engagement with the segmental end of the lever 74 and in position to be engaged by the sleeve 62^a of the actuator arm 20 62 when the latter is moved toward the same. When the parts are in the position shown in Fig. 13, movement of the arm against the said spring plunger 76 will not perform any function, but when the lever 74 25 is moved by the last step of movement of the disk 54, the segmental end of lever 74 will be in position to be engaged by plunger 76, so that when moved by the above noted oscillation of the actuating lever 62, the 30 latch plate 30 will be moved toward the right in respect to Fig. 13, thereby disengaging the same from the lock lug 29 of case shell 27, and this, of course, releases the said shell so that it may be lifted from working 35 position, provided, however, that the knob 63 first be removed from the stem 62. Preferably, said stub is detachably secured to said stem by a pin 63^a (see Fig. 2).

To prevent the above noted manipulation 40 required to release the case lock, from operating the ratchet release device and thereby causing the sliding bolt 56 to be returned to its normal position, a blank tumbler should be used. This blank tumbler may 45 be very much like the tumbler 46, but should not have a projecting lug, its function being to prevent finger 68 from engaging with the coöperating ratchet 45. This blank tumbler may be applied in addition to the four regular tumblers that are used in working a 50 combination. For example, one of the said tumblers 46 might be made double-ended with the lug omitted at one end.

In the illustrations, Figs. 1 to 15, inclusive, 55 the sliding bolt 56, when at the extreme right, will press an electrical contact 77 which is carried thereby, into engagement with an insulated contact 78 on the frame 28, and thereby close a circuit 79 which 60 will include the said two contacts 77 and 78. This circuit 79 may be assumed to be the ignition circuit of an explosive engine used in an automobile, but it may be any other electric circuit.

65 I, preferably also, combine a burglar

alarm with the lock above described, and this, as illustrated, comprises as follows:

The numeral 80 indicates a small lever that is intermediately pivoted to a bracket 81 on the frame 28, (see Fig. 13), and carries an electric contact 82 that is normally disengaged from, but is engageable with an insulated fixed electrical contact 83. These contacts 82 and 83 will constitute parts of an electric circuit which will include also a bell or signal device of some character, not shown. One end of this lever 80 is connected to one end of a rod 84, the other end of which is eccentrically pivoted to one of the above noted ratchets 45. The rod 84 70 80 has a headed end that works freely through the connected end of the lever 80, and that same end of the said lever is subject to a light coiled spring 80^a. The other end of the lever 80 is arranged to be engaged and held by the hook-like end of a curved spring latch 85 that is normally sprung downward against a stop pin 86 on the sliding bolt 56. When the sliding bolt 56 is in its locked position shown in Fig. 13, if an incorrect 90 manipulation of the actuating stem 62 is made, in an attempt to work the combination, the ratchets 45 are operated and then, of course, the particular ratchet 45, to which the rod 84 is pivoted, will be oscillated, and this will move the lever 80, so as to force its contact 82 into engagement with contact 83 and its free end into engagement with the hooked end of latch 85. Latch 85 95 will then hold the alarm circuit closed until, by the proper working of the combination sliding bolt 56 has been moved to the right into unlocked position, as already described. Under movement of the sliding bolt 56 toward the right, pin 86, operating 100 on the curved portion of latch 85, releases the same from the lever 80, and permits spring 80^a to then restore lever 80 to normal position shown in Fig. 13, thereby, of course, cutting out the alarm.

110 Figs. 16 to 20 illustrate a form of lock especially adapted for use as a door lock. In this form of lock, so-called a door lock, all of the parts from the actuating arm to the disk 54 and its crank stud 55, and including the ratchet release or restoring parts are, or may be, identical with those illustrated in Figs. 1 to 15, inclusive. In this arrangement, however, the lock bolt 87 which corresponds in some instances to the sliding bolt 56, is outwardly spring-pressed by a spring 88 and is moved against the tension of said spring, or retracted, by the cam stud 55 of the disk 54, operating on a bell crank 89. This bell crank 89 is suitably pivoted 115 to the frame 28, and that arm thereof, that is not engaged by the stud 55 is engageable with a stud 87^a on the lock bolt 87 (see particularly Figs. 16 and 18). Bell crank 89 120 is also subject to a light coiled spring 89^a 125

130

which tends to normally hold the same against a fixed stop 90. In a door lock, the knob 63 will be at the outside of the door. To operate or retract the lock bolt from the inside of the door, an arm 91 within the case, is also engageable with the stud 87^a and is normally held against a fixed stop by a coiled spring 92. This arm 91 is on the angular inner end of a shaft 93, which, at the inner side of the lock, has a finger piece 93^a, by means of which the same arm 91 may be moved against the tension of spring 92 to retract the bolt 87, as stated. The burglar alarm attachment in this modified form of the lock, is much on the same plan as that previously described and includes the same rod 84. This rod 84 is connected to a bell crank 94 that carries an electrical contact 95 that is engageable with a coöperating electrical contact 96 on the lock bolt 87, when and only when the said lock bolt is in a projected position shown in Fig. 16. The numeral 97 indicates a spring latch on the lock bolt 87, which, when the lock bolt is projected, will engage bell crank 94 and lock the same with electrical contacts 95 and 96 engaged until lock bolt 87 is again retracted.

The construction illustrated in Fig. 20 is like that illustrated in Fig. 17, except that the outer end of the lock bolt 87 is beveled and reversible. The lock illustrated in Figs. 21 to 25, inclusive, is designed as a lock for the transmission of an automobile. In this form of the lock, all of the parts from the actuating arm to the disk 54 and its cam stud 55, are, or may be, identical with those illustrated in Figs. 1 to 15, inclusive, including, of course, the ratchet or release, or restoring device. In this arrangement, the cam stud 55 operates on an arm 98 on the upper end of a vertical lock shaft 99, which, near its lower end, has a lock arm 100. This lock arm 100 has a segmental free end that is engageable with the peripheral channel 101 of a lock bolt 102 that is mounted to slide vertically through the case and is yieldingly pressed upward by a coiled spring 103. The lower end of this lock bolt in the construction here illustrated, is connected by a bell crank 104 and link 105, to some movable part of the transmission mechanism, such, for example, as to the lower end portion or gear parts of the shift lever 106. The alarm device here shown, includes a bell crank 107 that is connected to the rod 84 and carries an electrical contact 108 that is engageable with a fixed insulated electrical contact 109. In the position shown in Fig. 23, the alarm is in operating position, the contacts 108 and 109 being held engaged by the action of a spring-pressed dog 110 on one of the arms of the bell crank 107. When the arm 98 is moved outward and engages the dog 110 and moves the same so that its

free point is beyond a shoulder 111 of said bell crank 107, the bell crank 107 is permitted to return to normal position which separates the contacts 108 and 109, thus cutting out the alarm.

The term "tumbler" is herein used in a broad and liberal sense to include the progressively set elements upon which the actuator arm and stem 62 operate when properly manipulated. The expression "tumbler actuator" is also used in a broad sense to include a device, which, by proper movement, will engage and operate the above noted elements or so-called tumblers and gears. The ratchets 45 illustrate one possible form of tripping element, which, when moved by a proper manipulation of the tumbler actuator will, through coöperating devices, cause the tumblers and associated connections to be restored to zero or neutral positions.

What I claim is:

1. A combination lock comprising a multiplicity of circumferentially spaced interconnected combination devices, progressively set in respect to each other for movement to operative positions, and a non-rotary actuator movable radially from a central position toward any one of said devices and arranged to act in a predetermined order on the operatively set combination devices.

2. A combination lock comprising a multiplicity of circumferentially spaced rotary combination devices connected for simultaneous rotation and each comprising a tumbler, the said tumblers being progressively set in respect to each other for movement to operative positions, and a non-rotary tumbler actuator movable radially from a central position toward any one of said tumblers and arranged to act in a predetermined order on the operatively set tumblers.

3. In a combination lock, the combination with a group of combination devices circumferentially spaced around a central point, of an actuator operative thereon in a predetermined order by movements radially from the said central point, and means for automatically restoring the said combination devices to zero position by a movement of the actuator out of the predetermined order representing the operative combination.

4. A combination lock comprising a multiplicity of circumferentially spaced rotary combination devices connected for simultaneous rotation and each comprising a tumbler, the said tumblers being progressively set in respect to each other for movement to operative positions, and a tumbler actuator movable from a central position toward any one of said tumblers and arranged to act in a predetermined order on the operatively set tumblers, and means for automatically restoring the said combination devices to zero position by a movement of the actuator out

of the predetermined order representing the operative combination.

5. A combination lock comprising a multiplicity of circumferentially spaced rotary combination devices connected for simultaneous rotation and each comprising a tumbler, the said tumblers being progressively set in respect to each other for movement to operative positions, and a non-rotary tumbler actuator movable radially from a central position toward any one of said tumblers and arranged to act in a predetermined order on the operatively set tumblers, the said tumblers being set at different altitudes, and the said actuator having axial adjustment shifting it from positions for engagement with lower into position for engagement with upper tumblers.

6. A combination lock comprising a multiplicity of circumferentially spaced rotary combination devices connected for simultaneous rotation and each comprising a tumbler, the said tumblers being progressively set in respect to each other for movement to operative positions, and a tumbler actuator movable from a central position toward a one of said tumblers and arranged to act in a predetermined order on the operatively set tumblers, and an actuator guide limiting the movements of said actuator to radial lines limiting the movement of said actuator to lines radiating from said central position toward the several tumblers.

7. A combination lock comprising a multiplicity of circumferentially spaced rotary combination devices connected for simultaneous rotation and each comprising a tumbler, the said tumblers being progressively set in respect to each other for movement to operative positions, a tumbler actuator movable from a central position toward any one of said tumblers and arranged to act in a predetermined order on the operatively set tumblers, the said tumblers being set at different altitudes, and the said actuator having axial adjustment shifting it from positions for engagement with lower into position for engagement with upper tumblers, and an actuator guide limiting the movements thereof to lines radiating from said central position toward the respective tumblers, and the said actuator having a shoulder portion movable from a position below to a position above said actuator guide, and conversely.

8. A combination lock comprising a multiplicity of circumferentially spaced interconnected combination devices including upper and lower tumblers, of a non-rotary tumbler actuator movable radially from a central position toward any one of said tumblers and arranged to act in predetermined order on the operatively set tumblers, and the said actuator having axial adjustment shifting it from position for engage-

ment with lower into position for engagement with upper tumblers, and vice versa.

9. In a combination lock, the combination with a group of combination devices circumferentially spaced around a central point, of an actuator operative thereon in a predetermined order, by movements radially from the said central point, yielding means tending to restore said tumblers to zero positions, a retaining dog normally operative to hold said tumblers in progressively set positions, and interconnected tripping devices, one for each of said tumblers operative when actuated to release said retaining dog and permitting said tumblers to be restored to zero positions, the said tumblers when operated in the proper progressive order preventing said tripping device from being opened by the said tumbler actuator, but which tumbler actuator, when moved out of the predetermined proper order, being operative on the approaching tripping device to effect the release of said retaining dog.

10. In a combination lock, the combination with circumferentially spaced tumbler shafts, of tumblers and tumbler gears rotatable with said tumbler shafts, a central gear connecting said tumbler gears for common rotation, tripping gears loose on said tumbler shafts, a central gear connecting said tripping gears for common rotation, ratchet devices rotatable with said tripping wheels, yielding means tending to independently restore said tumblers and ratchet devices and the respective connected elements to zero positions, a retaining dog normally operative on the said central gear which is connected to said tumbler gears, to hold the same in progressively set positions, and a tripping element on the said central gear which is connected to said tripping gears, operative on said retaining dog to release the same, and a non-rotary tumbler actuator movable radially from a central position toward any one of said tumblers and arranged to work the combination by operation in the proper predetermined order on said tumblers but when operated in an improper order, acting upon said ratchet element of the approaching tripping devices to effect the release of said retaining dog, thereby permitting said tumblers to be automatically restored to zero positions.

11. A combination lock comprising a multiplicity of circumferentially spaced interconnected combination devices, progressively set in respect to each other for movement to operative positions, and a non-rotary actuator movable radially from a central position toward any one of said tumblers and arranged to act in a predetermined order on the operatively set combination devices, and spring means yieldingly holding said tumbler actuator in its central inoperative position.

12. A combination lock comprising a multiplicity of circumferentially spaced inter-

connected combination devices, progressively set in respect to each other for movement to operative positions, and an actuator movable from a central position toward any one of said tumblers and arranged to act in a predetermined order on the operatively set combination devices, the said tumbler actuator being supported on a universal joint for oscillating movements toward and from the respective combination devices.

13. A combination lock comprising a multiplicity of circumferentially spaced interconnected combination devices, progressively set in respect to each other for movement to operative positions, a non-rotary actuator movable radially from a central position toward any one of said devices, and arranged to act in a predetermined order on the operatively set combination devices, and 20 means for re-adjusting the devices to vary or reset the combination.

14. A combination lock comprising a multiplicity of circumferentially spaced interconnected combination devices, progressively set in respect to each other for movement to operative positions, a non-rotary actuator movable radially from a central position toward any one of said devices, and arranged to act in a predetermined order on the operatively set combination devices, and a lock element arranged to be progressively operated by said devices under a predetermined number of movements of the latter.

15. A combination lock comprising a multiplicity of circumferentially spaced inter-

connected combination devices, progressively set in respect to each other for movement to operative positions, a non-rotary actuator movable radially from a central position toward any one of said devices, and arranged to act in a predetermined order on the operatively set combination devices, a lock element arranged to be progressively operated by said devices under a predetermined number of movements of the latter, and an adjustable device for varying the number of movements of said devices required to operate said lock element.

16. A combination lock comprising a multiplicity of circumferentially spaced interconnected combination devices, progressively set in respect to each other for movement to operative positions, a non-rotary actuator movable radially from a central position toward any one of said devices and arranged to act in a predetermined order on the operatively set combination devices, an inclosing casing for said lock mechanism, a lock for said casing, and connections between said case, lock and said combination lock mechanism operative to release said case lock by manipulation of said combination lock mechanism in addition to that required to work the combination proper.

In testimony whereof I affix my signature 65 in presence of two witnesses.

DANIEL F. CARMICIEL.
